GEORGE T. TRUNDEL, OF CLEVELAND, OHIO, ASSIGNOR TO THE AMERICAN MULTIGRAPH COMPANY, OF CLEVELAND, OHIO, A CORPORATION OF OHIO.

COMPENSATING DEVICE FOR RIBBON-FEEDING MECHANISM.

1,115,991.

Specification of Letters Patent.

Patented Nov. 3, 1914.

Application filed June 21, 1913. Serial No. 774,976.

To all whom it may concern:

Be it known that I, GEORGE T. TRUNDEL, residing at Cleveland, in the county of Cuyahoga and State of Ohio, have invented a certain new and useful Improvement in Compensating Devices for Ribbon-Feeding Mechanism, of which the following is a full, clear, and exact description, reference being had to the accompanying drawings.

10 This device relates to printing devices in which the ink for the impression is carried by an inked fabric periodically fed to bring a fresh face to the type.

15 The object of the invention is to provide a simple and effective device enabling the fabric to be wound on and paid off of a spool as the printing member reciprocates, while accommodating itself to a gradual feed of the ribbon to bring a fresh face to the type.

20 To this end, the invention consists of a peculiar combination of spring re-winder and frictional-slip device for the take-up spool. This will be hereinafter more fully explained and the essential characteristics set out in the claims.

25 My compensating device is shown herein as embodied with an oscillating printing machine adapted to print circular letters with changeable addresses. One stroke of the machine is designed to print the letter and address, and the opposite stroke thereof to uncover the address from the ribbon, so that the address plate may be conveniently removed, and another one substituted for it.

30 In the drawings, Figure 1 is an end view of a printing machine equipped with my compensating device; Fig. 2 is a vertical transverse section of the same on a plane parallel with Fig. 1 looking in the opposite direction; Fig. 3 is a front elevation of such printing machine, sectioned axially of the platen; Fig. 4 is an axial section of the compensating device; and Fig. 5 is an end view of such device.

35 Referring by numerals to the parts shown in the drawings 10 and 11 indicate the upright end plates of the frame connected by a base portion 12. Rotatably mounted between the end plates is a drum 13. This drum, as shown, consists of a segment carrying parallel overhanging rails 14 (a few of which are indicated in Fig. 2) adapted to hold lines of grooved type. The segment is 40 shown as removably mounted on a rotatable

frame consisting of the shaft 15 and the end members 16 and 17. The segment is shown as locked to the shaft by a hook 18. Coacting with the type on the drum is a rotary platen 20, which is shown as loosely journaled on a shaft 21 having eccentric extensions journaled in the frame plates 10 and 11. A detented lever 23 on the end of the shaft 21 furnishes means for swinging that shaft to adjust the presentation of the platen to the printing drum. The platen and drum are geared together by a gear 30 on the drum, meshing with a gear 31 connected with the platen. Any suitable means may be employed to oscillate the drum and platen, as, for example, the crank 33 on the projecting end of the shaft 15.

45 To supply ink to the type carried on the printing drum, I mount within the drum (that is, between the rotary end members 16 and 17) a ribbon spool 40. An inked fabric 41 is wound on this spool and extends from it, toward the front of the machine, about the edge of the type segment to the payout spool 43, which is shown as carried by 50 the stationary frame in front of and near the top of the drum.

55 A suitable friction device is provided between the platen 20 and its shaft 21, the effect of which is to cause the rotation of the platen in the printing direction to turn the shaft with the platen, to raise the platen into engaging position, while a reverse rotation of the platen turns down the shaft into idle position. In this movement, the detent 90 lever 23 swings from the "off" to the "on" position. These positions are determined by the positions of an adjustable arcual bar 45 (Fig. 1), which is locked by a set screw 46 and has depressions 47 and 48 in which the end of a spring-pressed plunger 49 on the detent lever is adapted to seat. To provide the desired friction between the platen and its shaft, I make a groove in the shaft and mount therein a double leaf spring 50, 100 which bears against the inner wall of the platen, as clearly shown in Fig. 3.

60 With the construction described, if the crank 33 is rotated in the left hand direction in Fig. 1 (right hand in Fig. 2) the paper fed between the drum and platen may be printed by the type on the drum acting through the ribbon against the platen.

65 The matter on the drum may consist of a circular letter of type and an address car- 110

ried by a removable plate, as indicated at 55 in Figs. 2 and 3. This plate may be of the form, for example, shown, described and claimed in application No. 535,747, of 5 H. C. Gammeter, filed December 31, 1909. Suffice it to say that the address plate is readily removable and easily locked in place. Accordingly, after the drum has been rotated far enough to print the sheet and discharge it from between the drum and platen, a reverse rotation of the drum (left hand direction in Fig. 2) turns down the platen and carries the address plate to a position adjacent to the top of the machine, 15 where it is uncovered by the fabric. This enables the address plate to be readily changed by hand as desired.

The present invention provides means for taking up and paying out the rear or upper 20 end of the fabric which is mounted on the spool 43. One of the features of this mechanism is that it accommodates the periodic feeding of the ribbon onto the spool 40 to present a fresh face to the type. It will be 25 convenient to first describe briefly the ribbon feed mechanism herein illustrated.

In the present machine it is convenient to supply means on the drum for holding and feeding a spool additional to the spool 40, 30 so that, when desired, the spool 43, instead of being mounted on the frame, may be mounted on the drum, and the machine used like a standard multigraph. Fig. 2 shows the spool 40 in the drum and a ratchet wheel 35 68 designed to carry the spool 43 but idle when the parts are in the position shown in Fig. 2. The spool 40 is mounted on a ratchet wheel 69. Coöperating with the respective ratchet wheels are pawls 62 and 63, 40 which are reciprocated automatically as the drum rotates. It is to be understood that, as shown in Fig. 2 only the pawl 63 is active and the pawl 62, which might coöperate with the ratchet 68, is idle.

45 To automatically reciprocate the pawls, as well as to cause them to shift from the full to the empty spool automatically, I may employ the mechanism shown, described and claimed in Patent No. 997,615, granted 50 July 11, 1911, to The American Multigraph Company as assign of H. C. Gammeter. Only so much of that mechanism as is here concerned is shown in the drawings, and reference is made to that patent for a fuller 55 description. As shown in the drawings, there is a bar 60 yoking around the main shaft and reciprocable in a radial direction and carrying a plate 61, on which are pivoted the pawls 62 and 63, which are under 60 the influence of the spring 64. Suitable means (as an eccentric strap surrounding a stationary eccentric) connected with the reciprocating bar causes the pawl carrier to reciprocate.

65 In the present invention I provide a de-

tent pawl 66 adapted to engage the ratchet wheel 69 to hold the gain made in feeding the spool 40. This pawl is shown as pressed against the ratchet 69 by a spring 67 which acts on a tail of the pawl and enables it to 70 be swung over into the opposite direction entirely free from the ratchet 69. This is the position of the pawl when the spool 43 is mounted on the drum and the automatic ribbon reverse employed.

75 My compensating device proper is of the form shown in detail in Fig. 4, and consists of mechanism carried within the journal box 70 and having a gear 71 meshing with the main gear 30. The journal box 70 has 80 ears 73 extending from it by which it is secured to the frame plate 10. The gear 71 has a hub or flange 75 by which it is journaled within the journal box 70. At the other end of this box is a collar 76 having a 85 similar hub 77 journaled within the bore of the box. The two hubs are connected together by a helical spring 80 anchored at its ends to the respective hubs. Within the gear 71 and collar 76 is mounted the sleeve 90 82. This sleeve is locked to the collar 76 by the set screw 83. The sleeve has an extended disk-like head 85 with a smooth outer face. Against this face bears a fiber or other washer 86, and on the outer side 95 of this washer is a head 87. Extending through the head 87 through the washer 86 and into the bore of the sleeve 82 is a pin 90. This pin has a head portion 91, which seats in a similar recess in the outer face of the 100 head 87, and then comes a cylindrical portion, and then a smaller cylindrical portion 92. The opposite end of the latter portion is internally threaded, and carries a screw 94 which has a head overhanging the space 105 between the reduced portion 92 and the sleeve 82. In this space is a helical spring 95 compressed between the head 94 and an inward projection or flange 96 of the sleeve 82. This spring 95 serves to establish friction 110 between the head 87 and the head 85, the frictional wear coming on the washer 86 and the amount of this friction being regulated by the screw 94.

115 The central pin 90 of the compensator has a short stud 97 extending toward the other end of the machine, and the head 87 has an eccentrically positioned stud 98 in the same direction. The spool 43 has a central opening which is journaled on the stud 97, and 12 one of its heads has an eccentric opening which receives the pin 98. Accordingly, the spool and head 87 are interlocked to revolve together. The spool is pressed in this direction by reason of the engagement 12 of a spring pressed plunger 100 (Fig. 3) with the other end of the spool. This plunger is shown as mounted in a bracket 101 on the frame plate 11. The plunger is provided with a head 102, by which it may be 1

drawn outwardly to free the spool. A compression spring 103 tends to force the plunger inwardly to maintain engagement with the spool.

With the construction described, the gear 71 turns the spool 43 in the unwinding direction when the drum is turned forwardly to print. As the diameter of the ribbon roll on the spool 43 is ordinarily less than that of the pitch circle of the gear 71, it follows that the spool is not unwound by means of a gear as fast as the drum pulls the ribbon from the spool. Accordingly, the spool itself must turn faster, and this is accomplished by the spring connection 80 between the gear and the spool, this spring being wound up as the ribbon pulls off from the spool.

By the time the printing stroke is completed the spring 80 has been put under an increased tension by the pull of the ribbon as described. Now when the direction of the stroke is reversed at the end of the printing operation, the gear 71 winds the spool 43 in the direction to take up the ribbon. This movement of the drum delivers the ribbon to this take-up spool faster than the gear would wind in that spool, and thence the spring 80 unwinding, gives the rest of the rotation to the spool, so that it takes up the ribbon fed by the drum.

From the above description it will be apparent that the ribbon plays off of and on to the spool 43 as the drum is fed forwardly or backwardly. As this movement, however, is a compound of that given by the gearing and by the spring, a much more constant tension is kept on the ribbon than if the spring supplying such tension were anchored to a fixed point.

The ribbon feed mechanism on the drum is so set that, on the rearward stroke of the drum the receiving spool 40 is turned one tooth of the ratchet. Accordingly, not as much fabric goes back onto the spool 43 as came off of it. The result of this is that, with each stroke, the tendency is to wind the spring 80 tighter. To prevent the spring tension becoming excessive or interfering with the feed, the frictional slip device described is provided. As soon as the tension of the spring reaches the desired maximum, the head 87 connected with the spool simply slips on or with the washer 86, instead of transmitting movement to the spring 80. Accordingly, the spring tension on the ribbon is constantly maintained approximately constant.

The friction controlling the slip is adjusted by the screw 94, so that the slippage substantially corresponds to the periodic feed of the ribbon. That is to say, if there were not periodic feed, the pulling of the ribbon off of the spool 43, would put the spring 80 under tension almost to the point where

the slippage would take place. Then, as the ribbon is taken up by the ribbon feed on the reverse stroke, there is, on the succeeding forward stroke, enough slippage of the frictional clutch to compensate for the shortening of the reach of the ribbon.

The feeding of the ribbon from the spool 43 to the spool 40, is, of course, very gradual. When the ribbon has accumulated entirely on the spool 40 at the end of a large number of printing strokes, the machine is stopped and the two spools are removed and interchanged in position. Then the operation is continued as before.

Having thus described my invention, what I claim is:

1. The combination, with a printing couple having rolling contact for printing a plurality of lines, of an inking fabric, a spool on which one end of the fabric is wound, and from which it may be pulled, means for so pulling the fabric by an amount corresponding to the printing contact of the couple, a spring adapted to apply tension to the spool, and means for bodily moving the spring at a slower rate than the movement of the spool controlled by the pull of the fabric.

2. The combination, with a printing couple having rolling contact, of an inking fabric fed forward during such contact, a spool on which one end of the fabric is wound, a spring barrel adapted to apply tension to the spool, and means for bodily rotating the spring barrel independently of the pull of the fabric.

3. The combination, of a movable type bed, an inking fabric connected at one end with the bed, a rotatable spool on which the other end of the fabric is wound and from which it may be pulled by the movement of the type bed, a spring barrel adapted to apply tension to the spool, and means for bodily rotating the spring barrel at a slower rate than the rotation of the spool controlled by the fabric pulling from it.

4. The combination of a movable type bed, a platen adapted to coöperate with the bed, a fabric extending between them and being fed forward during the printing operation, a spool carrying the rear end of the fabric, a rotatable driver for said spool, and a spring interposed between the driver and spool.

5. The combination of a printing couple, an inking fabric, a spool carrying one end of such fabric, a driver, and a spring connecting the same with said spool, said driver being adapted to turn the spring in the same direction as the ribbon pulling off of the spool turns the spool.

6. The combination of a movable type bed, a platen coacting therewith, an inking fabric having one end carried by the bed, a spool carrying the other end of such fabric, a

rotatable driver, and a spring connecting the same with said spool, said driver being adapted to turn the spring in the same direction as the ribbon pulling off of the spool turns the spool.

7. The combination of a printing member, a coöperating platen, an inking fabric extending between the same, means for pulling the forward end of the fabric, a rotatable spool for carrying the rear end of the fabric, said spool being rotated by the fabric passing off of it as the printing member moves forward, a spring connected with said spool, and gearing between the spring and the printing member.

8. The combination of a printing member, a coöperating platen, an inking fabric extending between the same, a rotatable spool carrying one end of the fabric, said spool being rotated by the fabric passing off of it as the printing member moves, a coiled spring, one end of which is connected with the spool, and a gear connected with the other end of the spring, said gear being geared with the movable bed.

9. The combination of a movable bed, a coöperating platen, an inking fabric extending between the same, means for holding the forward end of the fabric to the bed, a rotatable spool for carrying the rear end of the fabric, said spool being rotated by the fabric passing off of it as the bed moves forward, a coiled spring, one end of which is connected with the spool, and a gear connected with the other end of the spring, said gear being geared with the movable bed.

10. The combination of a printing drum, a gear thereon, a platen coacting with the drum, an inking fabric adapted to extend between the drum and platen, means for carrying the fabric forward with the drum, a spool on which one end of the fabric is wound, a gear connected with the gear on the drum, and a spring and slip connection between the spool and its gear.

11. The combination of a printing drum, a gear thereon, a platen coacting with the drum, a fabric adapted to extend between the drum and platen, a spool on the drum carrying one end of the fabric, a spool on which the other end of the fabric is wound, a gear connected with the gear on the drum, and a spring between the last mentioned spool and its gear.

12. The combination of a printing drum having a gear, a gear meshing therewith, a spool, a spring connected at one end with the spool and at the other end with the gear last mentioned, and a fabric mounted on such spool and adapted to coact with the drum.

13. The combination of a printing drum having a gear, a gear meshing therewith, a spool, a spring connected at one end with

the spool and at the other end with the gear last mentioned, a spool carried by the drum, and a fabric mounted on said spools.

14. The combination of a movable printing bed, a ribbon spool mounted thereon, means for periodically feeding said spool to wind up the ribbon thereon, a pay-out spool mounted on fixed axis, a spring connected with the last mentioned spool, and means for bodily rotating said spring in the unwinding direction when the ribbon is pulled off of its spool and in the winding direction when the ribbon is fed back toward such spool.

15. The combination of an oscillating printing drum, a ribbon spool mounted thereon, means for periodically feeding said spool to wind up the ribbon thereon, a pay-out spool mounted independently of the drum, a coiled spring connected with the last mentioned spool, and means for bodily rotating said spring in the unwinding direction when the ribbon is pulled off of its spool, and in the winding direction when the ribbon is fed back toward such spool.

16. The combination of an oscillating printing drum having a gear, a gear driven thereby, a spool, a coiled spring connected at one end with the spool and at the other end with the gear last mentioned, a spool mounted on the drum, means for periodically turning the last mentioned spool, and a fabric mounted on said spools.

17. The combination of a movable printing bed, a ribbon spool mounted thereon, means for periodically feeding said spool to wind up the ribbon thereon, a pay-out spool mounted on a fixed axis, a coiled spring connected with the last mentioned spool, means for bodily rotating said spring in the unwinding direction when the ribbon is pulled off of its spool, and in the winding direction when the ribbon is fed back toward such spool, and a slip connection between the spring and its spool.

18. The combination of a movable printing member, a coöperating platen, an inked fabric extending between the two, a spool on which the forward end of the fabric is wound, means for periodically rotating said spool to wind in the fabric, another spool on which the rear end of the fabric is mounted, and mechanism for rotating the last mentioned spool, said mechanism including a spring enabling the spool to turn faster than the rotating mechanism would turn it.

19. The combination of a movable printing drum, a coöperating platen, an inked fabric extending between the two, a spool on the drum on which the forward end of the fabric is wound, means for periodically rotating said spool to wind in the fabric, another spool on which the rear end of the

fabric is mounted, and mechanism geared with the drum for rotating the last mentioned spool, said mechanism including a spring enabling the spool to turn faster than the rotating mechanism would turn it and a slip connection between the spring and its spool.

20. The combination of a movable printing member, an inking fabric, a spool carrying

10 one end of the fabric, means for periodically rotating said spool to wind in the fabric, a spool carrying the other end of the fabric, and gearing between the last mentioned spool and the printing member, 15 said gearing including a spring enabling the spool to turn at a different speed from the gearing.

21. The combination of a movable type-carrying member, a coöperating platen, a 20 fabric extending between the two, a spool on which the forward end of the fabric is wound, means for periodically turning said spool to wind in the fabric, a spool on which the rear end of the fabric is wound, a gear 25 connected with the printing member, and a helical spring between said gear and the last mentioned spool.

22. The combination of a movable type-carrying drum, a coöperating platen, a 30 fabric extending between the two, a spool on the drum on which the forward end of the fabric is wound, means for periodically turning said spool to wind in the fabric, a spool on the frame on which the rear end 35 of the fabric is wound, a gear connected with the printing drum, a helical spring between said gear and the last mentioned spool, and a slip connection between said spring and the last mentioned spool.

40 23. The combination of a movable printing member, a spool mounted thereon, means for periodically rotating said spool, an inking fabric wound on said spool, a second spool on which the other end of the 45 fabric is wound, a rotary member geared with the printing member and alining with said spool, and a coiled spring having one end connected with the rotary member and the other end with its alined spool.

50 24. The combination of a movable printing member, a spool mounted thereon, means for periodically rotating said spool, an inking fabric wound on said spool, a second spool on which the other end of the 55 fabric is wound, a rotary member geared with the printing member and alining with said second spool, a helical spring, one end of which is connected with said rotary member, a friction device connected with the

60 other end of said spring, and a coöperating friction device connected with the last mentioned spool.

25. The combination of a movable printing drum having a gear, a ribbon spool 65 mounted in the drum, means for automati-

cally partially rotating said spool, a second spool outside of the drum mounted parallel therewith, a fabric running from one spool to the other, a gear meshing with the gear on the drum, and a helical spring, 70 one end of which is connected with such meshing gear, and the other end with such outside spool.

26. The combination, with a printing couple, of a fabric through which impressions may be made, a spool on which said fabric is wound, and a compensating device connecting said spool with one member of the couple, said device consisting of a spring, a slip connection and gearing.

75 27. The combination, with a printing couple, of a fabric through which impressions may be made, a spool on which said fabric is wound, a compensating device connecting said spool with one member of the couple, said device consisting of a gear connected with the couple, a helical spring, one end of which is connected with the gear, a friction device with which the other end of the spring is connected, and a coöperating 80 friction member connected with the spool.

28. The combination, with a printing couple, of a fabric through which impressions may be made, a spool on which said fabric is wound, a compensating device connecting said spool with one member of the couple, said device consisting of a stationary journal box, a friction head having an extension rotatable within the box, a rotatable gear, a helical spring surrounding the 100 extension end connected at one end to the extension and at the other end to the gear, a coöperating friction device, and a connection between it and the spool.

95 29. The combination of a movable printing member, an inking fabric, adapted to be fed forward as the member prints, a spool on which one end of the fabric is wound, a compensating spring barrel connected with said spool and comprising a stationary 110 journal box, a gear having a hub journaled within the box, a friction head having a sleeve journaled within the hub, a spring connected at one end to the hub and at the other end to the sleeve, a coöperating friction head connected with the spool, a central pin for holding said heads in frictional engagement, a compression spring surrounding said pin within the bore of the sleeve, and means for adjusting the 120 compression of said spring.

30. The combination, with a printing couple, of an inking fabric, a spool on which the same is wound, and a compensating spring barrel for unwinding or winding 125 up the ribbon according to the movement of the couple, comprising a pair of friction members, a compression spring, and an adjusting screw for varying the friction, one member of such friction device being con- 130

connected with the spool, a take-up spring connected at one end with the other member of said friction device, and means connected with the other end of the last mentioned spool and geared with the movable member of the printing couple.

31. The combination, with a printing couple, of an inked fabric and a ribbon spool therefor, of a compensating driving connection for said spool comprising a pair of coöperating friction members, one of which is connected with the spool, a spring for forcing said members into contact, a

screw for adjusting said spring, another spring connected with the other member of 15 said friction couple, and a gear connected with a movable member of the printing couple and having the other end of the last mentioned spring connected to it.

In testimony whereof, I hereunto affix 20 my signature in the presence of two witnesses.
